UNITED STATES PATENT OFFICE.

JOSEPH A. VOGELMANN, OF BROOKLYN, NEW YORK.

SELF-FILLING FOUNTAIN-PEN.

940,909.

Specification of Letters Patent. Patented Nov. 23, 1909.

Application filed February 25, 1909. Serial No. 479,886.

To all whom it may concern:

Be it known that I, JOSEPH A. VOGELMANN, a citizen of the United States, residing at Brooklyn, in the county of Kings and 5 State of New York, have invented certain new and useful Improvements in Self-Filling Fountain-Pens; and I do declare the following to be a full, clear, and exact description of the invention, such as will enable 10 others skilled in the art to which it appertains to make and use the same.

My invention relates to fountain pens and particularly to self-filling pens of this character.

15 The object of the invention is the provision of a simple and easily operated pen which will be cheap to manufacture and which will have no joint at its forward or ink-distributing end, thus absolutely preventing leakage which otherwise might occur.

A further object of the invention is to provide an ink-reservoir with a valve plunger sliding therein adapted to suck ink from 25 a well or other suitable source to the ink-reservoir through the ink-distributing end and to automatically open the valve in the plunger so that the ink will run into the reservoir and not be forced out of the pen 30 holder when the plunger is forced to normal position.

With these and other objects in view, the invention consists of certain novel features of construction, combination and arrangement of parts, as will be more fully described and particularly pointed out in the appended claim.

In the accompanying drawings: Figure 1 is a longitudinal sectional view; Fig. 2 is 40 a transverse section, on the line 2—2 of Fig. 1; Fig. 3 is a transverse sectional view on the line 3—3 of Fig. 1; and Fig. 4 is a longitudinal sectional view, with the plunger partly retracted and showing how the pen 45 is used to suck up ink from a well or other suitable source.

Referring more especially to the drawings, 1 represents a tubular body having a valve chamber 2 arranged at one end, adjacent the 50 pen-holder 3, which is secured therein by cementing or otherwise. Adjoining the valve chamber 2 and in the rear end thereof is an ink-reservoir 4 which is closed at the rear end of the pen by a pair of plugs 5 and 6, the former threaded into the tubular body 55 1, and having a socket in its outer end to

receive the latter. Secured to the plug 6 and passing through an enlarged aperture 7 in the plug 5 is a plunger rod 8 which is connected to the apertured plunger 9 mounted upon the reduced end 10 of the plunger and held in position upon the reduced end by a shoulder 11 and a valve plate 12, the latter being screwed upon the end of the reduction 10. The plunger, as shown, is 65 provided with a pair of arcuate slots 13 so arranged in the plunger that they may be covered by the valve plate 12. It will be noted that the plunger is cup-shaped with its side walls extending into the ink-reservoir so that little or no room is taken up thereby and also that the plunger rod 8 is reduced along its entire length, except adjacent the plunger where it is enlarged to 70 form the shoulder 11. The plug 6 is provided with a knurled nut or head 14, by which the same may be unscrewed from its socket in the plug 5. As the rod 8 is secured to the plug 6 the plunger rod and valve plate turn with respect to the plunger until the 75 latter is engaged with the face of the plunger, at which time the plunger will be moved with the plate. After the plug has been completely withdrawn from its threaded engagement with the plug 5, the plunger may 80 be drawn up into the ink-reservoir to thus draw in the ink from the well or other suitable source and thereby fill the ink-reservoir. It will be noticed that when the plunger is again forced forward in the ink-reservoir the reduced part 10 of the rod 8 will 85 slide freely through the plunger, permitting the plate 12 to free itself therefrom and allow egress of the ink from one side of the plunger to the other. When the plug 6 is 90 again screwed into the plug 5, the shoulder formed by the reduced part 10 engages the plunger and forces it to normal position, where it remains adjacent the valve chamber 2. 95

Both ends of the pen are tapered, as is usual, as shown at 15, to receive the protecting cap 16, and the pen-holder 3 is channeled at 17, as is usual, to permit the outflow and in-flow of ink.

100 From the foregoing description, taken in connection with the accompanying drawings, the construction and operation of the invention will be readily understood without requiring a more extended explanation.

110 Various changes in the form, proportion and the minor details of construction may

be resorted to without departing from the principle or sacrificing any of the advantages of this invention, as defined in the appended claim.

5 Having thus described my invention, what I claim as new and desire to secure by Letters Patent of the United States, is:—

10 A fountain pen comprising a tubular body having an enlarged chamber in one end thereof, a channeled pen holder closing the end of the body adjacent said chamber, a piston mounted for reciprocation in said body and having a plurality of passage ways therethrough, means to reciprocate

15 said piston, and means carried by the reciprocating means for closing the passages in the piston during one movement thereof, said means adapted to lie within the chamber when inactive so as to permit the flow of ink therearound to the pen holder. 20

In testimony whereof I have hereunto set my hand in presence of two subscribing witnesses.

JOSEPH A. VOGELMANN.
